METHOD OF PRODUCING METAL LATH

Harvey M. Gersman, New York, N. Y., assignor to
 Ferrex Corporation, New York, N. Y., a corpora-
 tion of Delaware

Application May 29, 1939, Serial No. 276,316

5 Claims. (CL. 164—6.6)

This invention relates to improvements in metal lath and to a method of expanding metal which is suitable for the production of such lath.

Various of the processes heretofore proposed for the manufacture of lath of the character referred to have involved angular displacement of the strands as an incident to the expansion of the slotted blanks. Such displacement increases substantially the size of the openings defined by the strands as the latter are caused to assume positions which are edgewise with respect to the plane of the sheet. The relative large size of the openings and the angularity of the strands have the objection that only a slight resistance is offered to the passage of plaster through the openings. Hence, in order to avoid the waste which would otherwise occur, it has been the practice to apply the plaster in coats, the initial or scratch coat being relatively thin and having as its primary purpose the filling of the openings to prevent passage through them of the material of the subsequently applied heavy or browning coat.

The principal object of the present invention is to overcome the above objection, this object contemplating a lath characterized by a strand arrangement which will render a scratch coat unnecessary and enable a substantial saving in plaster and in the time required to apply the latter.

A further object is to provide a lath having a substantial measure of stiffness.

A still further object is a process suitable for producing the lath described which can be carried out rapidly and with apparatus of simple design.

The invention is illustrated in the accompanying drawing in which:

Figure 1 is a plan view of apparatus suitable for practicing the process.

Figure 2 is a side elevation of the apparatus.

Figures 3, 4 and 5 are enlarged views taken along lines 3—3, 4—4 and 5—5, respectively, of Figure 1.

Figure 6 is a fragmentary view in plan of the final product.

Figure 7 is an enlarged section taken along line 7—7 of Figure 6.

Figure 8 is an enlarged fragmentary view in plan of the final product.

In carrying out the process a sheet 10 of suitable gauge is passed through a pair of slitting rolls 11 and 12 in which it is formed with parallel longitudinally extending rows of slits. The latter provide strands 13 which are connected by extensions 13a and bonds 14, the slits 15 of alternate

rows being in staggered or break-joint relation with respect to the slits 16 of intermediate rows and preferably being shorter than the latter.

From the rolls 11 and 12 the sheet passes to a pair of forming rolls 17 and 18, one of which is shaped to provide annular flutes 19 which correspond in number to the strands 13 and the other of which is formed with mating embossments 20. The crests of the flutes 19 engage the linear portions of the sheet which include the long slits while the embossments 20 force the longitudinally extending zones between the long slits into the flutes. The strands 13 and the connecting portions containing the short slits are thereby arched while median creases 21 which are collinear with the long slits are formed in the bonds 14.

Upon emerging from the forming rolls the sheet is expanded to the desired width, preferably by the application of forces which act parallel to the plane of the sheet. This is in accordance with conventional practice and apparatus of standard design (not shown) may, therefore, be employed. As the sheet is stretched in the manner described, the bond sections at the opposite sides of the creases 21 fold and the strand extensions at the opposite sides of the short slits pivot away from one another and bend at their points of juncture with the strands and bonds, the angular displacement of the extensions being supplemental to, and hence being facilitated by, the original small displacement effected by the forming rolls. The extensions at each end of each strand turn in opposite directions. Hence, in so far as any twisting effect upon the strand is concerned, counteract one another. As a result the strands maintain their flatwise positions in the sheet as the latter is expanded.

From the foregoing it will be apparent that the lath produced in accordance with the invention is characterized by strands which are arranged flatwise in the plane of the sheet. The lath has the advantage, therefore, that while it may be expanded to the same degree as conventional diamond mesh lath, the distance between strands is substantially less, so much so that the necessity of a scratch coat is avoided. In this connection it will be noted that the only parts of the sheet presented edgewise are the bonds and the strand extensions, that is to say those parts which define the short slits. The openings which are produced when these parts are deformed in the manner described, however, are relatively small and represent only a small part of the total area. They are, therefore, not objectionable.

The slitting of the blank and the pre-shaping of the strands and connecting bonds are performed by rolls in a continuous operation. The process has the advantage, therefore, that it enables high speed production with apparatus of simple design. The arching of the strands not only insures angular displacement of the extensions in the proper direction but also has the further advantage that a substantial measure of stiffness is imparted to the sheet.

I claim as my invention:

1. The method of producing metal lath and the like which comprises slitting a sheet to provide parallel rows of strands connected by strand extensions and bonds and expanding the sheet to deflect said extensions toward edgewise positions and bend them at their points of juncture with said strands and bonds, whereby to effect separation of the strands while maintaining them substantially in their flatwise arrangement.

2. The method of producing metal lath and the like which comprises slitting a sheet to provide parallel rows of strands connected by strand extensions and bonds and expanding the sheet to fold companion sections of said bonds upon one another and deflect said extensions toward edgewise positions and bend them at their points of juncture with said strands and bonds, whereby to effect separation of the strands while maintaining them substantially in their flatwise arrangement.

3. The method of producing metal lath and the like which comprises slitting a sheet to provide parallel rows of strands connected by strand extensions and bonds, rolling the sheet to arch

said strands and crease said bonds along median lines and expanding the sheet to fold said bonds along said median lines and deflect said extensions toward edgewise positions and bend them at their points of juncture with said strands and bonds, whereby to effect separation of the strands while maintaining them substantially in their flatwise arrangement.

4. The method of producing metal lath and the like which comprises slitting a sheet to form parallel rows of slits, the slits of alternate rows being in staggered relation with respect to the slits of intermediate rows and being shorter than the latter, whereby to provide parallel rows of strands connected by strand extensions and bonds and expanding the sheet to deform said extensions and effect separation of the strands while maintaining them substantially in their flatwise arrangement.

5. The method of producing metal lath and the like which comprises slitting a sheet to form parallel rows of slits, the slits of alternate rows being in staggered relation with respect to the slits of intermediate rows and being shorter than the latter, whereby to provide parallel rows of strands connected by strand extensions and bonds, rolling the sheet to arch said strands and crease said bonds along median lines and expanding the sheet to fold said bonds along said median lines and deflect said extensions toward edgewise positions and bend them at their points of juncture with said strands and bonds, to thereby effect separation of the strands while maintaining them substantially in their flatwise arrangement.

HARVEY M. GERSMAN.
